JOHN C. SHAW, OF BROOKLYN, NEW YORK, ASSIGNOR TO KELLER MECHANICAL ENGINEERING CORPORATION, OF BROOKLYN, NEW YORK, A CORPORATION OF NEW YORK.

BOURDON-TUBE SPRING.

Application filed April 20, 1925. Serial No. 24,670.

My invention relates more particularly to a reinforcement for the Bourdon spring, to prevent distortion or destruction of the tube by excessive gauge pressure. In pressure 5 gauges subjected to high pressures, it may occur, occasionally, that excessive pressures are applied to the gauge which will expand the Bourdon tube beyond the elastic limit of the material of the tube and give it a set, 10 which will destroy the accuracy of the gauge. Furthermore, Bourdon tube springs are frequently ruptured by excessive pressure, thereby destroying the usefulness of the gauge.

15 The object of my improvement, therefore, is to provide means for limiting the expansion and distortion of the Bourdon tube spring, so that it cannot exceed the elastic limit of the material of the tube and in 20 this manner will protect the gauge against destruction or defective readings.

Heretofore, where gauges are to be subjected to variable high pressures, it has been the practice to thicken the walls of the tube 25 to thereby protect the gauge, the thick walls preventing excessive pressures from distorting or rupturing the tube, but obviously, this method decreases the sensitiveness of the gauge. A further object, therefore, of my 30 improvement is to provide a plurality of uniformly spaced substantially annular reinforcing devices preferably comprising a plurality of spaced rings extending throughout the length of the Bourdon spring and fitting 35 loosely thereabout, the space between the rings and the wall of the tube being such that only a predetermined amount of expansion or distortion of the tube will be permitted and this amount will be well within the elastic limit of the metal of the tube. 40 This method of protection will permit the use of a comparatively thin walled tube, which will make for a greater sensitiveness in the gauge.

45 One form of my improvement is illustrated in the accompanying drawings, in which Fig. 1 is a plan view of a Bourdon tube spring, provided with my improvement; Fig. 2 is a transverse section of the tube, 50 showing the relation between the tube and the protecting rings surrounding the same; Fig. 3 is a partial view of the strip carrying

and supporting the protecting rings, and Fig. 4 shows one of the rings.

Referring to the drawings, A is a Bourdon tube spring, which may be of ordinary construction, and since the Bourdon spring is well known in the art, no further description thereof will be required. In the present instance, the Bourdon tube is preferably surrounded by a plurality of thin sheet metal rings B, uniformly spaced apart throughout the effective length of the Bourdon tube spring, as indicated in Fig. 1 of the drawings. The rings B are preferably provided 60 with laterally projecting lugs C, which extend through equally spaced punch holes in a metal strip D, and are secured to the latter by heading over the lugs C, as indicated at E in Fig. 2 of the drawings. The Bourdon tube A is of the usual flattened construction, the flattening being radially of the curvature of the spring, as indicated in Fig. 2 of the drawings, and the rings B fit 65 loosely thereabout. The space F between the flattened walls of the Bourdon tube A and the rings B is preferably considerably 70 greater than between the curved walls of the tube, as clearly indicated in Fig. 2 of the drawings. This space permits the Bourdon tube to be distorted the normal predetermined amount, within the elastic limit of 75 the material, after which the walls will contact with the inner edges of the rings B and the latter will prevent any additional distortion, which under excessive or unusual pressure might exceed the elastic limit of 80 the material of the tube A.

Obviously, this construction permits the 85 use of a thinner walled Bourdon tube A, the thickness of the walls being determined by the material used and the capacity of the gauge in which the Bourdon spring is to be used, and the sensitiveness required. When these factors have been determined, 90 the rings B are proportioned to permit the maximum amount of expansion or distortion for the tube, that would be required for the maximum reading of the gauge, and any excess pressure would be taken by the rings B 95 and in this manner the tube is protected from further distortion, which might result in rupturing or giving a set to the tube. When the pressure is reduced, the Bourdon 100

tube will again come back to normal because its elasticity has not been affected and, therefore, the readings of the gauge will remain accurate, even though temporarily subjected to excessive pressures. Furthermore, as previously pointed out, the use of a thinner tube makes for greater accuracy and sensitivity in the gauge.

While I have shown and described the preferred form of my improvement, it will be understood that I do not wish to be limited to the specific construction shown, for obviously, various modifications in the specific construction may be made without departing from the spirit and scope of the invention.

I claim:—

1. A Bourdon tube spring reinforcement, comprising a Bourdon tube with a plurality of loosely fitting reinforcing ribs surrounding the same and means for uniformly spacing said ribs apart throughout the length thereof for limiting the expansion of the tube under pressure.

2. A Bourdon tube spring reinforcement, comprising a Bourdon tube provided with a plurality of thin sheet metal rings, loosely fitting the tube and uniformly spaced apart

throughout its length for preventing excessive expansion thereof, and means for holding said rings in spaced relation.

3. A Bourdon tube spring reinforcement, comprising a Bourdon tube a plurality of thin metal rings surrounding and arranged transversely of the tube, said rings being slightly spaced from the wall of the tube, the spacing being greater on the flattened sides of the tube to thereby permit a predetermined amount of expansion of the tube, and means for holding said rings in spaced relation throughout the length of the tube.

4. A Bourdon tube spring reinforcement, comprising a Bourdon tube, flattened radially of the curvature of the spring; a plurality of thin sheet metal rings surrounding said tube, the thin edges of said rings being in radial planes with respect to the center of the spring, said rings fitting the tube loosely and with a greater space between the rings and the flattened sides of the tube to thereby permit a predetermined amount of expansion, and means for holding said rings uniformly spaced apart throughout the length of the tube.

JOHN C. SHAW.
